UNITED STATES PATENT OFFICE.

PERCY C. SMITH, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRICAL SWITCHING APPARATUS.

Application filed December 5, 1922. Serial No. 604,977.

To all whom it may concern:

Be it known that I, PERCY C. SMITH, a citizen of the United States, residing at East Orange, in the county of Essex, State of New Jersey, have invented certain new and useful Improvements in Electrical Switching Apparatus, of which the following is a full, clear, concise, and exact description.

This invention relates to electrical switching apparatus generally and more especially to switching apparatus of the character employed in telephone exchange systems.

The object of the invention is an electrical switching device, serving to establish connections to the circuits of a group, in which an improved mechanism operates to allot said circuits for use in order.

A feature of the invention relates to a switch of the character described, for making connection to the trunks or circuits of a group, wherein an operating member individual to each trunk reacts with an allotting mechanism upon the operation of the switch to allot the next trunk in order for use.

Another feature relates to an arrangement wherein a number of trunks are divided into groups and subgroups with individual allotting devices for each group serving to allot the subgroups of each group in succession.

Such other and further features as are contemplated by the present invention will become more thoroughly understood from the following description and also from the attached claims.

In the drawing Fig. 1 is partial front view of a switching mechanism showing the allotting device. Fig. 2 is a side view of the structure shown in Fig. 1. Fig. 3 is an enlarged detail illustrating the allotting device. Fig. 4 shows the adaptation of a plurality of allotting devices to serve a large group of trunks or circuits together with control circuits for determining the operation of said devices. Fig. 5 is a diagrammatic illustration of the control circuits of the allotters whereby the subgroups of each of a number of groups of trunks are taken for use in rotation.

Although the switching device embodying this invention is applicable to various uses, it is particularly suited for establishing connections between incoming circuits or trunks

and outgoing circuits or trunks in a telephone exchange system. By arranging the incoming circuits in coordinate relation to the outgoing circuits and providing the necessary mechanical switching members, any incoming circuit may be connected electrically to any of the outgoing circuits.

Referring to the drawing, it will be considered for the purpose of explaining the mechanical construction and operation of the switch that its purpose is to effect connection between incoming circuits such as the circuits 1, 2, 3 and 4, 5, 6 and outgoing circuits or trunks such as the trunk 61. Each of the incoming circuits is represented in the switch by a plurality of plain bare wires arranged in a horizontal position. Only two such circuits are illustrated in the drawing; the first of which comprises the three stationary bare wires 1, 2 and 3 and the second of which comprises the three wires 4, 5 and 6.

Each of the outgoing trunks is arranged in intersecting relation to each of the horizontal circuits and constitutes a vertical row of flexible wire contacts. The trunk 61, for instance, appears in the first vertical row at the left in Fig. 1 and is provided with a set of flexible wire contacts for each of the horizontal or incoming circuits. The three flexible contacts 7, 8 and 9 are secured to an insulating block 60 and project to a point where their free ends cooperate with the respective wires 1, 2 and 3 of the horizontal circuit. The three flexible wire contacts 10, 11 and 12 representing the same trunks 61 are also secured to the block 60 and project to a point where they cooperate with the stationary wires 4, 5 and 6 of the second horizontal circuit. Similarly, trunk 61 is equipped with as many other sets of flexible contacts as there are horizontal circuits in the switch. The same is true of other trunks which are represented by other vertical rows.

The flexible contacts 7, 8 and 9 project through diagonal slots 13, 14 and 15 in the operating card 56 which is composed of insulating materials. The card 56 is supported by means of a flexible spring 58, one end of which is secured to the block 60 and the other end of which normally rests on the upper conductor 1. With the spring 58 resting on the conductor 1 the flexible conductors 7, 8 and 9 repose in the upper edges of the respective diagonal slots out of en-

gagement with the respective stationary wires 1, 2 and 3. Similarly, the flexible conductors 10, 11 and 12 pass through diagonal slots 16, 17 and 18 in the operating card 57. The card 57 is supported by the spring 59 which is secured to the block 60 with its free end resting on the upper conductor 4.

Moreover, each of the outgoing trunks is provided with an individual operating bar, three of which bars 19, 20 and 21, are shown. The bar 19 is individual to the trunk 61 and is provided with a flexible wire finger for each of the operating cards. The finger 26 is individual to the card 56, the finger 27 is individual to card 57, and, similarly, other fingers are provided for as many other operating cards as there are for this particular trunk. Normally, the flexible fingers 26, 27, etc. are in the position shown in Fig. 1 out of coacting relation with the respective insulating cards 56, 57, etc.

In addition to the vertical operating bars 19, 20, 21, the switch is equipped with a number of horizontal intersecting bars 22 and 23. The bar 22 is individual to the horizontal circuit 1, 2, 3, the bar 23 is individual to the second horizontal circuit shown, and, similarly, other horizontal bars (not shown) are individual to corresponding circuits. The bar 22 is provided with a plurality of levers 28, 94, 95, etc., one arranged in proximity to an insulating card relating to each of the outgoing trunks. In like fashion the horizontal operating bar 23 is equipped with a number of operating levers 29, 96 and 97, one for each of the outgoing trunks.

The horizontal bars 22 and 23 are rotated by means of individual electromagnets 24 and 25. The upper bar 22 is shown in its rotated position while the lower bar 23 is illustrated in its normal or released condition.

Besides the mechanism thus far described, the switch is provided with a number of selecting or controlling cards 30, 31, 32, etc. These cards are made of insulating material and each is individual to one of the vertical rows of trunk contacts. The card 30, for instance, is individual to the vertical row of contacts associated with the vertical bar 19, representing the trunk 61. The cards 31 and 32 are in like manner individual to the next two vertical rows of contacts representing the two succeeding trunks. These cards are provided with large openings or windows at each point of cooperation between a set of flexible wire contacts and a set of stationary wire contacts. These windows are of sufficient size to permit the set of flexible contacts to project therethrough as best seen in Fig. 2. The purpose of these selecting card members is to cooperate with the allotting device in the manner to be described hereinafter to allot

the several trunks in a definite order for use. The allotting mechanism shown at the bottom of Figs. 1 and 2 and in Figs. 3 and 4 includes a segmental plate or table 33 which is fashioned to present a series of steps or notches (Fig. 3). The table 33 is supported on brackets 41 and 42 which are rigidly attached to the shaft 40, which in turn, is supported in bearings 43 and 44 for rotation. A helical spring 99 is wound about the shaft 40 and is secured at one end to the bearing 43 and at the other end to the collar 98 rigidly attached to the shaft. The effect of the spring 99 is to constantly urge the supporting table 33 in the direction of the arrow shown in Fig. 3 or in a forward direction as viewed in Fig. 1.

The extreme left end of the shaft 40 carries the plunger of a solenoid 51. The solenoid when energized draws the shaft 40, together with the supporting table 33, to the left against the tension of the spring 99. When deenergized the spring 99 carries the displaced parts back to their normal position.

A second solenoid 52 is provided for the purpose of restoring the supporting table 33 to its normal position in a rotary direction, after it has been advanced to its extreme set position by the spring 99.

Supporting table 33 is further equipped with a series of pins 37, 38, 39, etc., each located, as seen in Fig. 3, at the edge of one of the steps in said table. These pins, which project downwardly, cooperate with levers attached to the vertical operating rods. The rod 19, for example, has the lever 34 extending laterally to a point where its free end is in proximity to the pin 37. If the table 33 is at the proper point in its operation, the pin 37 will encounter the upturned end of the lever 34 when the table 33 is drawn to the left. However, the pin 37 will not encounter the lever 34 at any other point in the rotation of the supporting table 33. In like manner pins 38 and 39 cooperate with levers 35 and 36 projecting from the respective vertical rods 20 and 21.

The selecting cards 30, 31 and 32 have at their lower ends the projecting portions 53, 54 and 55. When all parts of the switch are in normal position and the supporting table 33 of the allotting device is rotated fully to the left, see Fig. 2, the portions 53, 54 and 55 on the selecting cards escape the upper surface of the table 33 and permit the cards 30, 31 and 32 to fall to their lowermost position where the upper edges of the windows rest on the supporting springs 58, 59, etc. The card 32 is seen to be in this position while the other two cards 30 and 31 are shown in their upper positions with the portions 53 and 54 resting on the upper surface of the supporting table 33.

Assume that the switch is in its normal

position with all of the trunk selecting cards down. If it is desired to connect one of the horizontal circuits, such as the circuit 1, 2, 3, to an idle outgoing trunk, a circuit is first 5 established by applying ground to the start wire 100 in any well known manner. The start wire leads through the switch arm 50 and contact 101 through the winding of the solenoid 51 to battery. The solenoid 51 energizes and draws the shaft 40 and the supporting table 33 to the left. Since all parts 10 of the device are in their normal position, the pin 37 is exactly opposite the lever 34 carried on the first trunk bar 19. Consequently, the movement of the table 33 causes the pin 37 to engage the lever 34 and rotate the trunk bar 19. The rotation of the bar 19 carries the flexible fingers 26, 27, etc. to the left as shown in Fig. 1 and under the lower edge of the respective operating cards 56 and 57.

Next a circuit is established in any suitable manner for the operating magnet 24 and the bar 22 is rotated. The rotation of bar 22 carries the associated levers 28, 94 and 95 upward. The lever 28 in its upward motion encounters the positioned flexible finger 26 and the finger 26, in turn, engages the lower edge of the card 56 whereby said card is moved up against the tension of the supporting spring 58. The upward movement of the card causes the flexible wires 7, 8 and 9 to engage the respective conductors 1, 2 and 3 with a sliding action due to the diagonal slots 13, 14 and 15. Thus, the connection is established between the first idle trunk and the circuit 1, 2, 3. Inasmuch as none of the remaining trunk bars have been positioned, the other levers 94, 95, etc. fail to encounter the respective flexible fingers and, therefore, none of the other operating cards are disturbed.

As the operating card 56 commences its upward movement the supporting spring 58 bears against the upper edge of the window in the common selecting card 30 and the card 30 is carried upward also. When the card 30 has moved through a sufficient distance the projecting portion 53, against which the supporting table 33 is pressing under the influence of the spring 99, escapes the edge of said table. This permits the spring 99 to rotate the table 33 forward until the next step thereon encounters the projecting portion 54 of the next selecting card 31 representing the second idle trunk. The common selecting card 30 is now above the upper cylindrical surface of the table 33.

Next the solenoid 51 may be released 60 whereby the shaft 40 and table 33 are restored in the axial direction. When the table 33 rotates to select the next trunk, the pin 37 disengages the lever 34 whereby the vertical rod 19 restores to its normal position under the influence of a spring (not

shown). The rod 19 in rotating back carries all the remaining flexible fingers 27, etc. to their normal positions, while the finger 26 which was engaged by the lever 28 is held in its set position, due to the V-shaped edge of said lever 28. The magnet 24 is maintained energized and thereby holds the operating card 56 in its operated position to maintain the established connection.

The supporting table 33 on rotating forward to preselect the next idle trunk brings the second projecting pin 38 forward to a point where it coincides with the upturned edge of the lever 35 on the rod 20. When the next call comes in and the solenoid 51 is operated, the table is drawn to the left and pin 38 encounters the lever 35 to rotate the vertical rod 20 to prepare all sets of contacts relating to this particular trunk for operation. Next, one of the horizontal bars is operated and the desired horizontal circuit is connected to the second idle outgoing trunk. During the operation of the parts in establishing the second connection, the common selecting card 31 is drawn upwardly, allowing the table 33 to escape forward another step where it is stopped by the portion 55 on the third selecting card 32.

Although it has been explained as an example that the horizontal circuit 1, 2, 3 is connected to the first outgoing trunk, the drawing actually illustrates this horizontal circuit as being connected to the second outgoing trunk represented by the vertical bar 20.

In this manner the trunks are taken for use in strict succession, the operation of the switch in establishing a connection to one trunk causing the preselection of the next trunk to handle the next connection. For each trunk taken into use the allotting device rotates about the shaft 40 one step until finally the last trunk in the switch is taken. When this happens the supporting table 33, having rotated to its full off-normal position, causes the armature 112 which is rigidly attached to the bracket 41 and is loosely connected at its free end to the spindle 45 to depress the spindle to a point where the collar 46 engages the pivoted lever 48. The lever 48 moves the switch arms 49 and 50 from the terminals 101 and 102 to the terminals 103 and 104, respectively. If, at this time, ground potential again appears on the conductor 100 in case of another attempt to appropriate one of the trunks for use, the circuit of solenoid 51 is held open due to the position of the switch arm 50.

With the switch in its alternate position, a circuit is closed from ground through the arm 49, terminal 104, winding of the restoring solenoid 52 to battery. The solenoid 52 draws in its core, which acts on the pin 62, and rotates the allotting device including the card supporting table 33 back

to its normal position. As the table 33 rotates back to its normal position the common selecting cards 30, 31 and 32 drop back one by one to their normal positions in order that all idle trunks may again be taken for use in order. As the solenoid 52 rotates the shaft 40 to its full normal position, the spindle 45 is drawn upwardly to a point where the collar 47 engages the lever 48 and moves the switch arms 49 and 50 back to the terminals 102 and 101, respectively. The lever 48 has a resilient end the purpose of which is to produce a snap action in the movement of the switch arms 49 and 50 from the terminals 104 and 103 to terminals 102 and 101 respectively, when the supporting table is returned to normal and the collar 47 is effectively engaged with the lever 48. If the first selecting card 30 is still in an operated position when the supporting table is returned to its normal position and the solenoid 52 is then deenergized, the supporting table will rotate under the tension of spring 99 until it is stopped by the projection of the

second selecting card, and if the second card is also in an operated position the table will continue to rotate forward until it is stopped by the projection on the third selecting card and so on if the third card is in an operated position, until it is stopped by a card whose projection is in its lower or unoperated position. When ground is again placed on the starter wire 100, the solenoid 51 is operated and the first idle trunk in the series is taken for use in the manner explained.

Should any one of the trunks, after having been engaged, become idle during the time the common selecting card relating to such trunk is above the surface of the table 33, such trunk cannot again be taken for use unless all succeeding trunks that are idle have been used and the device restored to its normal position. Should certain of the trunks, taken into use during the operation of the allotting device, remain busy after the last trunk had been appropriated, the restoration of the allotting device does not interfere with the busy trunks. The common selecting cards are merely held in their uppermost positions by the supporting springs of the individual operating cards.

Any suitable circuit arrangement whereby the initiation of a call places a potential on the usual start conductor 100 and whereby the selection of the proper one of the horizontal operating magnets 24, 25, etc. is effected, may be employed with a switch of this character. Reference is made, for example, to the British patent to Western Electric Company, Limited, No. 183,438 of 1923, which shows one manner of bringing about the closure of the starting circuit and of completing circuits for the horizontal operating magnets of the switch.

Fig. 4 shows the invention applied to a switch of large capacity where a number of trunks or circuits which it is desired to allot for use for rotation is large. The size of the allotting device may be kept within the desired limits by employing a plurality of the supporting tables 33 in tandem. Fig. 4 shows three allotting units 70, 71 and 72 mounted on their individual shafts 73, 74 and 75 and controlled by the operating solenoids 76, 77 and 78. The individual restoring solenoids 79, 80 and 81 are used for restoring the separate devices to normal position. The supporting table 70 will accommodate the group of common selecting cards 81 (see Fig. 5). The next table 71 accommodates the group of cards 82 while the table 72 serves the last group of cards 83. The operating solenoids 76, 77 and 78 are operated in succession by the extension of the start wire 100 through contacts operated by the shafts 73, 74 and 75, respectively.

Referring particularly to Fig. 5 the trunks of the groups 81, 82 and 83 are divided into subgroups, there being three subgroups for each of these main groups. By means of the circuit arrangement shown the trunks of the first subgroup in the group 81 may be taken for use in strict rotation, whereafter the starting circuit is extended to the second main group 82 and determines that the trunks of the first subgroup of this second main group shall next be taken for use. After all these trunks have been used the starter circuit is extended and the trunks of the first subgroup of the third main group 83 are taken for use in order. Thereafter, the start circuit is extended back to the first main group 81 and the trunks of the second subgroup are taken for use. Next, the trunks of the second subgroup of the second group are taken and, thereafter, the trunks of the second subgroup of the third main group are taken for use. Lastly, the third subgroup of trunks in each of the three main groups are taken for use in the respective order.

With the allotting mechanisms in their normal positions the closing of starting conductor 100 completes a circuit through spring 106 and its lower contact, winding of solenoid 76 to battery. In the manner described the solenoid 76 causes the connection to be made to the first trunk and the individual selecting card 107 is elevated. After all of the trunks in the first subgroup have been taken for use the card 84, which is elevated when the last trunk is taken, permits the spring 106 to close its alternate contact. On the next call the start wire 100 is extended over the alternate contact of spring 106, spring 108 and its normal contact, winding of solenoid 77 to battery. In like manner the solenoid 77 may

be operated a number of times until all trunks in the first subgroup of the second group 82 are taken for use. When the last trunk in this subgroup is appropriated, the 5 common card 87 shifts the spring 108 to its alternate contact.

Hereafter the start wire 100 leads over the alternate contacts of springs 106 and 108, thence through the normal contact of 10 spring 109, winding of the third solenoid 78 to battery. After solenoid 78 has been energized a number of times and all trunks 15 in the first subgroup of the group 83 are employed the selecting card 90 elevates and shifts the spring 109 to its alternate contact. Subsequent calls now cause the closure of 20 the start wire 100 over the alternate contacts of springs 106, 108 and 109, thence through the normal contact of spring 110, winding 25 of solenoid 766 to battery. The solenoid 76 causes the selection of trunks in the second subgroup of the first main group 81 and when all of these trunks have been taken the common card 85 is raised to shift the 30 spring 110.

By inspection of the circuits it will be noted that subsequent calls will cause the second subgroup of the group 82 to be taken for use, thereafter the second subgroup of 35 the third group 83, then the third subgroups of each of the three groups 81, 82 and 83 in order.

When the last trunk in the last subgroup 40 has been taken, a common card 92 in elevating closes the contact spring 111 and a circuit is completed from ground through this spring and thence in parallel through the windings of solenoids 79, 80 and 81 to battery. Solenoids 79, 80 and 81 operate in 45 the manner explained to restore the allotting devices 70, 71 and 72 to their normal positions.

While the horizontal circuits 1, 2, 3 and 4, 5, 6, etc. are spoken of as incoming circuits 45 for the purpose of distinction it is plain that the circuits may constitute link circuits for interconnecting incoming lines or incoming trunks to the outgoing trunks illustrated in the switch. The manner in which these 50 horizontal circuits are employed as links is disclosed and described in the above mentioned British Patent 183,438 of 1923.

What is claimed is:

1. In combination, incoming circuits, outgoing circuits, separately movable contacts for effecting connection therebetween, a controlling member for each outgoing circuit, operating means for moving said contacts, means within said operating means for actuating each controlling member when the corresponding outgoing circuit is taken for use, and means associated with said members for allotting in definite order the outgoing circuits for use.
2. In combination, incoming circuits, out-

going circuits, separately movable contacts for effecting connection between the incoming and outgoing circuits, a controlling element for each outgoing circuit, means for operating said contacts, means controlled by 70 said operating means for actuating each controlling element when the corresponding outgoing circuit is taken for use, and means controlled jointly by said elements for allotting the outgoing circuits for use in a definite order.

3. In combination, a number of circuits, separately movable contacts for effecting connection with said circuits, a controlling member for each circuit, operating means 80 for moving said contacts, means controlled by said operating means for actuating each controlling member simultaneously with the operation of a contact set when the corresponding circuit is taken for use, and means controlled by said members for allotting 85 said circuits for use in order.

4. In combination, a number of circuits, separately movable contacts for effecting connection with said circuits, a movable card 90 for each circuit, operating means for moving said contacts, means controlled by said operating means to actuate each card when the corresponding circuit is taken for use, and means controlled by said movable cards 95 for allotting the circuits for use in succession.

5. In combination, a number of circuits each having a plurality of contact sets, operating means for operating any contact set 100 to make connection with the corresponding circuit, a slideable controlling member for each circuit and common to all contact sets thereof, means controlled by said operating means for actuating each controlling member when any set of contacts to which such member is common is operated, and means controlled by said members for allotting 105 said circuits for use.

6. In combination, a number of circuits 110 each having a plurality of contact sets, operating bars for actuating said contact sets to make connection with said circuits, a slideable controlling member for each circuit and common to all contact sets thereof, means associated with said contact sets and operated by one of said bars for actuating each controlling member when any set of contacts to which such member is common is operated, and means controlled by said members for 115 allotting said circuits for use.

7. In combination, a number of circuits each having a plurality of contact sets, operating bars for separately actuating any contact set to make connection with the corresponding circuit, a slideable controlling card 120 for each circuit common to all contact sets thereof, means associated with said contact sets and operated by one of said bars for actuating each card when any set of 125 contact sets and operated by one of said bars for actuating each card when any set of con-

tacts to which such card is common is operated and means controlled by the slidable cards for allotting said circuits.

8. In combination, a number of circuits each having a plurality of contact sets, operating bars for separately actuating any contact set to make connection with the corresponding circuit, a slidable controlling card for each circuit common to all contact sets thereof, a flexible element associated with each of said contact sets and operated by one of said bars for actuating each card when any set of contacts to which said card is common is operated and a mechanical allotting device cooperating with said cards to allot the circuits for use in succession.

9. In combination, a number of circuits each having a plurality of contact sets, operating means for operating any contact set to make connection with the corresponding circuit, a controlling member for each circuit and common to all contact sets thereof, means associated with said contact sets and actuated by said operating means to effectively move each controlling member when any set of contacts to which such member is common is operated, and a plurality of mechanical allotting devices cooperating with said members to allot said circuits for use in a desired order.

10. In combination, a number of circuits arranged in groups, contact sets for making connections with said circuits, a slidable controlling member for each circuit, operating means for moving said contact sets, a resilient element within said operating means for actuating each controlling member when the corresponding circuit is taken for use, and means controlled by said members for allotting for use a portion of the circuits in each group successively.

11. The combination with a number of groups of circuits arranged in subgroups of contact sets for making connection with said

circuits, a controlling member for each circuit, operating means for actuating said contact sets, a flexible bar associated with said operating means for actuating each controlling member when the corresponding circuit is taken for use, and means for selecting a first subgroup of circuits in each of said groups successively and then a second subgroup in each group successively, and so on.

12. The combination in a coordinate switch of a plurality of trunks each having a plurality of contact sets for making connection therewith, cooperating switch bars for actuating said contact sets, a controlling card individual to each trunk and common to all contact sets thereof, an element for displacing each card when any set of contacts to which such card is common is operated by one of said bars, and a mechanical allotting device cooperating with said cards to determine the order in which said trunks are taken for use.

13. The combination in a switching device of a series of trunks each having contacts for making connection therewith, means for operating said contacts, controlling members one for each of said trunks, a resilient bar within said operating means for actuating each controlling member when the corresponding trunk is taken for use, means controlled by each of said controlling members for allotting the next idle trunk of the series for use, means controlled by said allotting means for locking said controlling members in their operated positions, and means effective when the last of said series of trunks is taken for use for restoring said allotting means and for unlocking such of said controlling members as correspond to idle trunks.

In witness whereof, I hereunto subscribe my name this 1st day of December, A. D. 1922.

PERCY C. SMITH
